UNITED STATES PATENT OFFICE.

GEORGE D. KRATZ AND CHARLES WATTLEWORTH, OF AKRON, OHIO, ASSIGNEES TO THE FALLS RUBBER COMPANY, OF CUYAHOGA FALLS, OHIO, A CORPORATION OF OHIO.

DESIGN FOR A NONSKID TIRE.

Application filed February 18, 1922. Serial No. 759. Term of patent 14 years.

To all whom it may concern:

Be it known that we, GEORGE D. KRATZ and CHARLES WATTLEWORTH, citizens of the United States, and residents of Akron, county of Summit, and State of Ohio, have invented a new, original, and ornamental Design for a Nonskid Tire, of which the following is a specification, reference being had to the accompanying drawing, forming part thereof.

In said annexed drawing:—

Fig. 1 is a plan view of a portion of our improved tread; and Fig. 2 is a section on the line 2—2 of Fig. 1.

We claim:—

The ornamental design for a nonskid tire as shown.

Signed by us, this 15th day of February, 1922.

GEORGE D. KRATZ.
CHARLES WATTLEWORTH.
